UNITED STATES PATENT OFFICE

LAURA DOREMUS, OF NEW YORK, N. Y.

TOY

Application filed June 8, 1931. Serial No. 542,828.

My present invention relates to toy greenhouses, and aims to devise articles of the general character specified which are simple in construction, which may be conveniently and economically fabricated and assembled, which are neat and attractive in appearance, and which give the appearance or semblance of a hot-house having a series of small panes of glass in its side, end and roof members, but without the actual necessity of having the glass portions of such side and roof members made up of separate panes of glass, which would, of course, add greatly to the cost of the device and render it very fragile and more liable to injury and breakage than otherwise. Other objects and advantages of the devices of the present invention will in part be pointed out in detail hereinafter, and will in part be obvious to those skilled in the art to which the present invention relates.

In the accompanying specification I shall describe, and in the annexed drawing show an illustrative embodiment of the present invention. It is, however, to be clearly understood that my invention is not limited to the specific embodiment thereof herein shown and described for purposes of illustration only.

Referring to the drawing, in which I have shown the aforesaid illustrative embodiment of the present invention:

Fig. 1 is perspective view of the device;

Fig. 2 is a side elevation of the same;

Fig. 3 is an end elevation of the same;

Referring now to the aforesaid illustrative embodiment of the present invention, 10 indicates the bottom or floor member which may be made of a solid piece of wood, or may be pieced together in any desired fashion.

Associated with the floor or bottom member 10 are a plurality of side members 11 and 12, end members 13 and 14, and roof members 15 and 16 embodying the corner portions 17 and 18, respectively. It may here be stated in general that each of the side, end and roof members referred to is made up of a rectangular or square frame, in the case of the end members, embodying angular frame portions, preferably of wood, in which is inserted a single pane of glass, although in certain in-

stances the glass may consist of two or more separate members held in the particular frame. These frame members, containing their glass members, are constructed and may be assembled in the manner which will now be described in considerable detail herein:

Taking the side members 11 and 12, for example, to commence with, and assuming that the side members 11 and 12 are similarly constructed so that it will be necessary to describe in detail only one of such members, the side member 11, for example, may comprise the frame 111, which may be made up of four frame members 112, 113, 114 and 115, which may be mortised together or otherwise suitably secured at their corners. The frame thus made may hold securely in position a lattice or screen 116, which may be made of stiff wire, so that when the pane of glass 117, also held in the frame 111 and preferably positioned behind the lattice or screen 116, is seen through such lattice or screen, the side 11 of the toy greenhouse now being described will appear to contain a series of small panes of glass, whereas, in fact it consists of only a single pane of glass. At the same time, the screen or lattice work 116 serves to reinforce the structure and to protect the pane of glass 117. As already indicated, the side 12 is constructed similarly to the side 11 just described in detail.

Referring now to the end walls 13 and 14, here also these are similarly constructed so that it will be necessary to describe only one of the end walls, such as the end wall 14. It may here be stated that the corner portions 17 and 18 may be integral with the end portions 13 and 14, in which case the reference characters 17 and 18 designate, not separate corner members made up of complete frames and inserted panes of glass together with screen or lattice members, but the upper corner portions of the end walls 13 and 14 with which they are integral in all respects.

Describing now the end wall 14, the upper or corner portion of which has been designated by reference character 18, I have here a frame-work 141, which is made up of five instead of four frame members, for example, the members 142, 143, 144, 145 and 146. 100

- The frame members 142, 143, 144, 145 and 156 may be held together by having their joints mortised or otherwise suitably secured together. Here, also, as in the case of the side member 11, there is held within the frame the screen or lattice work 147 behind which is positioned the pane of glass 148, so that such pane of glass, seen through the lattice or screen member 147, appears to consist of a series of small panes of glass. Here the screen or lattice member 147 serves to reinforce the device and to protect the pane of glass 148, while giving the appearance and effect of a series of small panes of glass.
- I come now to the roof members 16 and 15. Except that the roof member 15 is hinged, as at 19 and 19' to the roof member 16, such roof members are substantially identical in construction and it will be sufficient for the purposes of the present specification to describe but one of them. Taking the roof member 15, for example, the same comprises the frame members 151, 152, 153 and 154, which may be mortised together at their points or corners, or otherwise suitably secured together, in a manner which will be readily apparent to those skilled in the art to which the present invention relates. The frame, generally designated by reference character 155, now has inserted therein the screen or lattice work 156 behind which is located the pane of glass 157. The screen or lattice work 156, therefore, serves the purpose of reinforcing the roof member 15 and to make the single pane of glass 157 appear as if made up of a series of small panes of glass.
- As already indicated, the roof member 15 is hinged to the roof member 16 which is preferably rigidly secured to one of the side members and to two of the end members of the structure as a whole. This makes it possible therefore to lift or raise the roof member 15 swinging the same about the hinges 19 and 19' so as to provide access to the interior of the structure as a whole.
- It may here be stated that each of the members making up any of the frames of the side, end and roof members is provided with a groove or channel in its inner edge surface to receive the pane of glass or lattice member. It may here also be stated that the various members making up the structure may be suitably secured together by any desired means, preferably by a series of screws which will therefore permit the device to be packed and shipped flat, and to be assembled in an altogether convenient and simple manner upon arrival at its destination.
- For example, the side members 11 and 12 and the end members 13 and 14, respectively, may be secured along their bottom edge portions to the floor or bottom member 10 by a series of screws 20 passing through the bottom member 10 into the lower frame members of the side and end walls of the device.

It may here also be stated that the end members may be so dimensioned as to be included at their sides within the end portions of the side members. Accordingly, the side and end members may be secured together by similar screws passing through the end portions of the side members into the adjacent end portions of the end members.

Finally, the roof member 16 may be secured by similar screws to the end members, and also to the top portion of the side member 12, the roof member 15, as already stated, being hinged at 19 and 19' to the roof member 16 so as to be capable of being swung about the hinges 19 and 19' to give access to the interior of the structure as a whole.

In conclusion, and in order to increase the similitude of the device to a real greenhouse, and also to reinforce the structure as a whole and to give it solidity and proper appearance, I provide a plurality of stands or benches 21, each of which may be made up of supporting blocks of wood or other suitable material 21 and 22, and a cross block 23, to which frustro-conical blocks 24 in the shape of flower pots may be secured, provided with the ornaments 25 giving the appearance of potted plants. These may be secured by screws or otherwise through the bottom or floor member 10 passing into the end blocks 21 and 22 of each of the stands or benches 20. The ends 23' and 23'' of the stands or benches 20, should be such as to come almost into contact with the interior faces of the panes of glass held in the side members 11 and 12, thus to assist in securing them in place in their respective frames so as to render the whole device more rigid and secure against injury and displacement.

This completes the description of the aforesaid illustrative embodiment of the present invention. The construction of such embodiment will, it is believed, clearly appear from the foregoing description. Likewise, the manner of assembling the device will clearly appear from the foregoing description and may be briefly summarized as follows:

The various bottom, or floor, side, end and roof members having been prepared in advance and arriving in disassembled or flat condition, together with the screws, panes of glass, screens or lattices, and hinges, the floor member is first taken, and then either the opposite side members or the opposite end members, or any or all of these in any desired succession, may be secured to the bottom or floor member by the screws already referred to. The fixed roof member is then applied to the end members and the associated side member and then the hinges applied to the ridge pole portion of the roof member, after which the hinged roof member is attached to the fixed roof member by the hinges already referred to.

Preferably before any of the members referred to have been applied to the floor member, the benches or stands may have been secured to the bottom member together with 5 their associated representations of flower pots and contained plants.

This completes the description of the manner of assembling the illustrative embodiment of the present invention. It will be 10 noted that the device is simple in construction, may be readily and conveniently fabricated and assembled, and, when assembled, presents the exact appearance of a greenhouse in which the side, end and roof members are 15 each made up of a series of panes of glass, although here but a single pane of glass is used which is given the appearance of a series of small panes of glass by lattice members or screens which not only serve to give the 20 solid pane of glass the appearance of being made up of a series of small panes of glass, but which serve also to reinforce the structure and to protect the large panes of glass. The stands or benches containing the 25 representations of flower pots and contained plants serve also to reinforce the device and, in particular, to hold in proper position the panes of glass in their respective side and end frames. It may here be stated that, if so 30 desired, each of the plants 25 may be constructed of an approximately exact or even scientific representation of a particular variety of plant or shrub and may bear a label 35 giving the name, common or scientific, or both, as desired, of the particular plant represented.

Other superiorities and advantages of the present invention, particularly as exemplified in the aforesaid illustrative embodiment of 40 the same, will readily occur to those skilled in the art to which the present invention relates.

What I claim as my invention is:

A toy greenhouse, comprising a supporting 45 bottom member, and a plurality of associated side and end members carried by said supporting bottom member, each of said side and end members comprising a plurality of channeled frame members forming a frame, and 50 a pane of glass and a covering wide-mesh screen member carried by said frame in the channels of said channeled frame members.

In testimony, whereof, I have signed my 55 name to this specification this 14th day of May, 1931.

LAURA DOREMUS.
